US0D1087301S

(12) **United States Design Patent** (10) Patent No.: **US D1,087,301 S**
(45) Date of Patent: ** Aug. 5, 2025

(54) **UNIVERSAL COUPLING**

(71) Applicant: **ADVANCED DRAINAGE SYSTEMS, INC.**, Hilliard, OH (US)

(72) Inventors: **Evan Joseph Geno**, Hilliard, OH (US); **Matthew Caleb Huizenga**, Hilliard, OH (US)

(73) Assignee: **Advanced Drainage Systems, Inc.**, Hilliard, OH (US)

(**) Term: **15 Years**

(21) Appl. No.: **29/871,380**

(22) Filed: **Feb. 17, 2023**

(51) LOC (15) Cl. **23-01**

(52) U.S. Cl.

USPC **D23/262**
